UNITED STATES PATENT OFFICE.

FRED A. BENNETT, OF CHICO, CALIFORNIA.

SELECTIVE SIGNALING SYSTEM.

Application filed August 29, 1927. Serial No. 216,019.

This invention relates generally to electrical systems in which one station may signal selectively to any one of a plurality of receiving stations. The invention is particularly 5 designed for use in telephone systems in which a plurality of telephone subscribers are connected to a common or party line.

It is an object of this invention to devise a selective signaling system which will operate 10 with a simple impulse code and which will utilize energy transmitted from the central or selecting station for effecting the desired signal response at one of the receiving stations.

15 It is a further object of this invention to devise a selective signaling system especially adapted for ringing the bells of subscribers of party telephone lines, which will require no special apparatus for the central ringing 20 station, and which will not necessitate batteries or other sources of energy at each of the subscribers' stations.

It is a further object of this invention to 25 devise a mechanism which may be readily incorporated with standard telephone systems so as to function to automatically connect the ringer of the telephone to the line in response to a particular combination of impulses.

30 Further objects of this invention will appear from the following description in which I have set forth the preferred embodiment of my invention. It is to be understood that the appended claims are to be accorded a range of equivalents consistent with the state 35 of the prior art.

Referring to the drawing:

Fig. 1 is a side elevational view illustrating diagrammatically the essential parts of the apparatus of this invention.

40 Figs. 2, 4 and 5 are similar to Fig. 1, but illustrate different operative positions of the selecting mechanism.

Fig. 3 illustrates the different code signals utilized for selectively signaling to a plural- 45 ity of stations.

Fig. 6 is a circuit diagram illustrating the manner in which the apparatus shown in Figs. 1, 2, 4 and 5 may be incorporated with a standard telephone system.

50 The invention may be outlined briefly as comprising a pair of switches which are adapted to be automatically closed to operatively connect the ringing magnets of a telephone to the telephone line, after a certain code has been transmitted from the central station. The selecting mechanism includes

a selecting magnet adapted to be permanently connected to the telephone line, and which is actuated upon the reception of each selector impulse to rotate a selector wheel. After a 60 predetermined number of selecting impulses have been received, the selective wheel has been moved to a position in which it causes closing of the contacts of one of the ringer switches. The contacts of the other switch 65 are adapted to remain open during the reception of selector impulses, but is adapted to close during the reception of a following long ringing impulse, and a portion of this ringing impulse is therefore 70 caused to pass thru the telephone ringing magnets. At the end of the long ringing impulse, means is provided whereby the selector wheel is returned to initial position in readiness for a new signal code. From the foregoing 75 it is clear that to effect a response at one particular station a certain number of selecting impulses are transmitted, followed by a relatively long signal or ringing impulse, and that to distinguish or select different stations a different number of selecting impulses 80 are utilized.

In the drawing I have not attempted to disclose a commercial type of apparatus, but have merely indicated the general character 85 of the different mechanical parts so that one skilled in the art may readily construct the same. The fundamental principles of the invention may be understood more readily by first referring to the circuit diagram of Fig. 90

6. In this diagram the lines L_1 and L_2 represent the usual subscribers' lines which lead from a telephone central and which are connected to a plurality of telephone subscribers A and B. In the ordinary telephone equipment each subscriber is provided with a suitable magnetic ringer 10 connected across the lines L_1 and L_2 in series with a ringing condenser 11. In this invention switches 12 and 13 are inserted in series with the ringer 10 95 so that both switches must be closed before a pulsating ringing impulse will effect an audible signal. The apparatus shown in Figs. 1, 2, 4 and 5 is for the purpose of effecting automatic closing of switches 12 and 13 in response to the reception of a certain number of selecting impulses. The motive element for each selective mechanism consists of the selector magnets 14 which are generally permanently connected across the lines L_1 and 100 L_2 in series with the condenser 11.

105 Referring now to Fig. 1 for a detail de-

scription of the selecting mechanism, the selecting magnets 24 are shown as provided with an armature 26 biased as by means of gravity to open position and adapted to reciprocate a member 27, which member is connected to the armature 26 thru a suitable lever 28. Also pivotally connected to the lever 28 is a pawl 29 which is adapted to engage a toothed wheel 31 pivotally mounted upon shaft 32. Rotation of ratchet wheel 31 is adapted to carry with it a selector wheel 33, and both ratchet wheel 31 and selector wheel 33 are biased to rotate in a clockwise direction by suitable means such as a spring 34. A projection 36 on the notched wheel 31 is adapted to engage a fixed member 37 and thereby limit rotation of the selector wheel.

The switch corresponding to switch 12 in the circuit diagram of Fig. 6 has been designated 22 in Fig. 1 and consists of the relatively movable contacts 38 and 39, the contact 38 being controlled by means of a member 41 which is pivotally mounted to the shaft 42. One end of member 41 is provided with a projection 43 which is adapted to be normally urged into contact with the periphery of the selector wheel 33, as by means of a weight 44 attached to arm 41. After the selector wheel 33 has been rotated a given amount, the projection 43 is adapted to drop into a notch 46 and thereby permit sufficient movement of arm 41 to close the contacts 38 and 39.

The switch designated as 13 in Fig. 6, has been designated 23 in Fig. 1 and comprises the relatively movable contacts 47 and 48. Normally these contacts remain closed but upon the reception of a series of selecting impulses, they are moved apart and remain so until the reception of a long ringing impulse, during which they close to cause the ringing current to pass thru the telephone ringers. This control over the contacts 47 and 48 is effected by means of a device which is set in motion at the beginning of the first selecting impulse and which moves sufficiently slow that it does not effect closing of the contacts before the beginning of a succeeding selecting impulse. A suitable mechanism which has been shown in the drawing consists of a bellows 51 which is biased towards closed position as by means of a weight 52, and which has provision for restricted escape of air so that when the bellows is moved to open position, it will return relatively slowly to closed position. One of the contacts of switch 23, say contact 48 is mounted upon the movable portion 53 of this bellows. For moving the bellows 51 to open position responsive to the reception of a selecting impulse, I have provided an arm 54 adapted to be actuated by reciprocation of the rod 27, and which is operatively connected to the movable portion 53 of the bellows as by means of an arm 56 having a pin and slot connection 57 with the movable portion 53.

For engaging the upper end of arm 54, there is provided an escapement member 58 which is pivotally mounted to the rod 27 as at 59. An extension of rod 27 is provided with a cam surface 61 adapted to ride upon the fixed member 62. When the selector magnets 24 are energized to actuate the armature 26, movement of rod 27 first carries with it the arm 54 by virtue of the escapement member 58, but near the end of movement of arm 27, engagement of cam surface 61 with the fixed member 62 effects disengagement of the escapement from arm 54, and thus permits this arm to slowly return to initial position together with the bellows 51. Fixed to the rod 27 there is also a detent 63 which is adapted to engage the arm 54 when the armature 26 is in closed position. The function of this detent will be later explained, altho it may be mentioned at this time that it serves to prevent complete closing of the bellows 51.

After a ringing operation has been effected it is desirable to automatically provide for a release of the selector wheel 33 so that this wheel may return to initial position. For this purpose I have shown a link 66 having a pin and slot 67 with the arm 41, and pivotally connected at its lower end to one arm of a lever 68, this lever being suitably journaled upon a pin 69. The other arm of lever 68 is adapted to be engaged by a member 71 which is carried by movable portion 53 of bellows 51. When the detent 63 is engaged with the arm 54 with armature 26 in closed position, switch 23 may be closed, but the bellows 51 cannot close sufficiently far to actuate link 66 to lift the projection 43 from the selector notch 46. However when the armature 26 is released as at the end of a ringing impulse, the bellows may close an additional amount which is sufficient to lift link 66 and arm 41, and thus disengage the projection 43 from notch 46, thereby permitting the selector wheel to rotate in a clockwise direction and return to its initial position.

In order to fully explain the operation of the device, it will be presumed that this particular apparatus has been constructed so that it will respond to a code consisting of two relatively short impulses of pulsating ringing current which may be termed selecting impulses, followed by a relatively long impulse of pulsating current, which may be termed the ringing impulse. Before any impulses have been received, the parts of the apparatus will be substantially as shown in Fig. 1 with switch 22 open and switch 23 closed. Upon the reception of the first selecting impulse, armature 26 is closed to actuate rod 27, and pawl 29 is engaged over a tooth of the notched wheel 31. Movement of rod 27 carries with it the arm 54 until the escapement member 58 is released by virtue of engagement of cam surface 61 with the stationary member 62. Movement of the arm 54

has caused opening of the bellows 51 and switch 23, and after release of arm 54 the bellows returns slowly toward closed position. This position of the apparatus with the 5 armature closed during the first selecting impulse and after the release of arm 54, is shown in Fig. 2. At the end of the first selecting impulse the armature 26 and rod 27 return to original position and movement of 10 the pawl 29 carries with it the notched wheel 31 and the selector wheel 33. The friction between the projection 43 and the periphery of the selector wheel 33 is sufficient to overcome the tension of spring 34, so that the 15 selector wheel will remain in this new position after release of pawl 29. The next selecting impulse begins shortly after the termination of the first impulse, and as has been shown in Fig. 4, the armature 26 is again 20 moved to closed position to cause pawl 29 to engage a new tooth of the wheel 31. Likewise the bellows 51 is again moved to open position as has previously been described with respect to the first selecting impulse. At the 25 end of this second selecting impulse the selector wheel 33 is rotated to bring the notch 46 in position to be engaged by the projection 43, and movement of arm 41 causes closing of the contacts of switch 22. The 30 last part of the second selecting impulse however does not cause energization of the ringing magnets as the bellows 51 keeps the switch 23 open until after the starting of the third long impulse or ringing impulse. At the 35 beginning of the final long ringing impulse, armature 26 is again closed and causes the arm 54 to be tripped. The bellows 51 then closes sufficiently far to permit closing 40 of the contacts of switch 23 at which time the arm 54 comes in contact with the detent member 63. Switch 23 is therefore closed during a part of the time that the long ringing impulse is being transmitted over the line, and again referring to the diagram of 45 Fig. 6, it will be seen that the closure of both of these switches causes the current to divide and to pass thru the ringing magnets 10 of the telephone. Thus the last part of the ringing impulse causing ringing of the telephone after closure of switch 23.

After the last long impulse has ceased, the armature 26 returns to open position as shown in Fig. 6. The detent 63 is thus removed from arm 54 so that bellows 51 is permitted to close 55 farther than it has during any part of the selecting or ringing operation. This farther closing of the bellows causes member 71 to engage the lever 68 and thus lift the link 66 to lift the arm 41 from the notch 46, thus permitting the selector wheel 33 to rotate under the tension of spring 34 and return to initial 60 position. The apparatus is now ready to receive a new code combination.

With the apparatus as described above, the 65 last long impulse will effect ringing of a

bell of a subscriber's telephone which is equipped with an apparatus which causes closing of both the switch 12 and 13 when two preceding short selecting impulses are received. If a long ringing impulse is preceded only by a short selecting impulse, then the projection 43 will not drop into the notch 46 and switch 22 will not be closed during the ringing impulse. Likewise if a combination is received having three selecting impulses preceding the long ringing impulse, then the selector wheel 33 will be moved to a position which will cause projection 43 to ride out of the notch 46 and thus keep the switch 22 open during the ringing impulse. 70 75 80

In practice a number of subscriber telephones are equipped with apparatus as described above. The only difference in the individual apparatus is that the notches 46 in the selecting wheels are arranged at different 85 points about the periphery thereof so that a different number of selecting impulses will be required to effect energization of the respective ringing magnets during the long ringing impulse. Assuming that there are 90 four stations which are adapted to be rung separately, referring to Fig. 3, the first station may respond to a single long ringing impulse. Similarly stations B, C, and D may respond 95 respectively to one short selecting impulse followed by a long ringing impulse, to two short selecting impulses, and to three short selecting impulses followed by the ringing impulse. Code signals of this kind correspond to the signals at present in use in telephone centrals for ringing different subscribers. 100

In order to provide for uniformity of installations, preferably all of the subscribers have a selecting apparatus of similar structure. These individual apparatuses are preferably adjustable, as by having the notch 46 adjustable with respect to the selector wheel, so that they may be set to respond to any given code combination. The subscriber's station which responds to a single long ringing impulse, preferably has its apparatus equipped with an auxiliary switch 123. The contacts of this switch are arranged to be closed only after the lapse of a 110 substantial time following energization of magnets 24. The contacts of this switch are then substituted in place of the contacts of switch 23, in the circuit diagram as shown in Fig. 6. The selector wheel for this first station has its notch 46 arranged in such a position that normally it is engaged by member 43. When a single long impulse is transmitted over the line, magnets 24 are energized and cause switch 123 to be opened to prevent 115 immediate ringing. However during the latter part of the long impulse, switch 123 is closed, and together with closed switch 22, closes the circuit thru ringer 10. When another code combination is received, say one 120 125 130

having two short selecting impulses followed by a long ringing impulse, the first short selecting impulse will not be sufficiently long to permit closing of switch 123 and thus other code combinations cannot effect ringing of this first station.

In some instances, a large number of selecting impulses may be transmitted in excess of the number of notches provided upon the 10 selecting mechanism. To prevent jamming of the selector wheel, I preferably provide the notch wheel 31 with a blank portion as shown so that after this wheel has been notched up a certain distance, further energization of the 15 selector magnet 24 will not effect further rotation of the selector wheel.

It is to be particularly noted that in this system the present alternating or pulsating ringing current of telephone systems is used 20 both to select the desired station and to supply the current to actuate the telephone ringer magnets, and that no local batteries or other source of electrical energy are required. Furthermore the apparatus may be readily 25 incorporated with existing telephone systems without making any elaborate alterations. Similar code combinations are at present being employed on party telephone lines although at present no selecting mechanism is 30 being utilized. With this system practically the same code combinations may be employed to operate the selecting apparatus and thus prevent ringing the bells of all telephones except that of the subscriber desired.

35 I claim:

1. In a telephone signaling system, a plurality of receiving stations connected to a common telephone line, each of said stations having ringing means adapted to be actuated by pulsating current, and at least two of said stations being provided with selecting switching means for operatively connecting said ringing means to the telephone line only after a long pulsating current impulse has been preceded by a definite number of short impulses, and means for effecting automatic resetting of said switching means after the termination of said long impulse, said means being automatically conditioned upon the termination of 45 said long impulse.

2. In a signaling system, a signal circuit, a response circuit, a pair of switches adapted to be closed for connecting the response circuit to the signal circuit, each switch having relatively movable contacts, a selecting magnet connected to said signal circuit, selector means adapted to be moved by said magnet to effect closing of one switch after the magnet has been energized by a definite number of 55 selecting impulses, means for normally biasing the contacts of the other switch toward closed position, means serving to move said latter contacts apart upon the reception of each selector impulse, means for retarding 60 closing of the contacts of said other switch

before the next selecting impulse is received.

3. In a signaling system adapted to effect signaling at a remote station in response to a signal code consisting of a definite number of short spaced selecting impulses followed by a long signal impulse, said system including a response circuit located at the receiving station, a pair of switches adapted to be closed for connecting the response circuit to the signal circuit, each switch having relatively movable contacts, a selecting magnet connected to the signal circuit, a selector member adapted to be moved by said magnet in response to each selecting impulse for effecting closing of one switch while the signal impulse is being received, means for normally biasing the contacts of the other switch toward closed position, means serving to move the contacts of said other switch apart upon the reception of each selector impulse, and means for retarding closing of the contacts of said other switch before the next selector impulse is received but permitting closing during reception of the long signal impulse.

4. In a signaling system adapted to effect signaling at a remote station in response to a signal code consisting of a definite number of short spaced selecting impulses followed by a long signal impulse, said system including a response circuit located at the receiving station, a pair of switches adapted to be closed for connecting the response circuit to the signal circuit, each switch having relatively movable contacts, a selecting magnet connected to the signal circuit, a selector member adapted to be moved by said magnet in response to each selecting impulse for effecting closing of one switch while the signal impulse is being received, means for normally biasing the contacts of the other switch toward closed position, means serving to move the contacts of said other switch apart upon the reception of each selector impulse, means for retarding closing of the contacts of said other switch before the next selector impulse is received, and means for effecting return of said selector member to initial position upon the cessation of the signal impulse.

5. In a signaling system adapted to effect signaling at a remote station in response to a signal code consisting of a definite number of short spaced selecting impulses followed by a long signal impulse, said system including a response circuit located at the receiving station, a pair of switches adapted to be closed for connecting the response circuit to the signal circuit, each switch having relatively movable contacts, a selecting magnet connected to the signal circuit, a selector member adapted to be moved by said magnet in response to each selecting impulse for effecting closing of one switch while the signal impulse is being received, means adapted to be tripped upon energization of the selector magnet for effecting movement of the contacts of said

other switch apart, means for effecting closing of said contacts after a period of time which is greater than the lapse of time between the beginning of each selector impulse.

- 5 6. In a telephone ringing system, adapted to selectively ring the bell of a telephone in response to a signal code consisting of a definite number of short spaced selecting impulses followed by a long ringing impulse, said system including a ringing circuit, a pair of switches adapted to be closed for connecting the ringing circuit to the telephone lines, each switch having relatively movable contacts, a selecting magnet connected to the telephone
- 10 lines, a selector wheel adapted to be rotated
- 15

by said magnet in response to each signal impulse for effecting closing of one switch while the ringing impulse is being received, means adapted to be actuated upon energization of said magnet for effecting closing of the contacts after a period of time which is greater than the period between the beginning of each impulse whereby said one switch is not closed until during reception of the long ringing impulse, and means for effecting automatic return of the selector wheel to initial position after cessation of the long ringing impulse.

In testimony whereof, I have hereunto set my hand.

FRED A. BENNETT.
